UNITED STATES PATENT OFFICE.

NORMAN B. CLABAUGH, OF FREDERICK CITY, MARYLAND.

IMPROVED WASHING-MACHINE.

Specification forming part of Letters Patent No. 35,669, dated June 24, 1862.

To all whom it may concern:

Be it known that I, NORMAN B. CLABAUGH, of Frederick City, in the county of Frederick and State of Maryland, have invented a new and useful Improvement in Washing-Machines; and I do hereby declare that the following is a full and exact description thereof, reference being had to the accompanying drawings, forming a part of my specification, and to the letters of reference marked thereon, like letters indicating the same parts in the figures, and in which drawings—

Figure 1 is a longitudinal vertical section of my improved washing-machine; Fig. 2, a like view of the pressure-board, and Fig. 3 an enlarged cross-section of the rubbing-ribs of the pressure-board.

In the drawings, A indicates a wash-tub of any convenient dimensions having an opening or angular slot, a, as shown partly in dotted lines in Fig. 1, cut in its sides to receive the axis or gudgeon, e, of a rubbing-cylinder, B, the bearings of the gudgeon of said cylinder resting in the bottom of said opening and being secured in place by a pin, a', as indicated in said figures. The ends of said cylinder are at their peripheries cut in the form of arcs of circles, which are eccentric to the axis e of the cylinder B, as at a², and upon which rubbing-boards C are secured, as shown, the forward working portion of each rubbing-board being nearer to the center of the axis e than its rear working portion. The working-faces of the rubbing-boards C are corrugated in the form of ribs d the entire length of the cylinder B, the form and diameter of said ribs being the same in the entire series of said boards surrounding the heads or ends of the cylinder.

Cleats i' are secured at one end of the machine, as indicated in dotted lines in Fig. 1, in which to receive the bearings i² of a cross-bar, i³, which supports a circular-formed weighted rubbing-board, H, having a working-face composed of a series of rubbing-plates, H', each of which plates is formed with a series of ribs, h', h², h³, and h⁴, of increasing height from rib h' to rib h⁴, as shown. This rubbing-board H is in width the same as the length of the cylinder B, and is made to articulate

freely upon its bearings i², and thus be brought up toward the cylinder B with a greater or less pressure, according as a greater or less leverage is exerted upon it by means of a weight, L, placed upon an arm, k, attached to its cross-bar i³, the pressure of said rubbing-board being governed by the position the weight L may occupy in either of the notches k', k², or k³ of the arm k, as the case may be.

Clothes being placed in the machine between the rubbing-board H and the cylinder B, and the cylinder rotated by the crank f, it will be perceived that the clothes will be subjected to a wedging pressure over each one of the rubbing-boards H', and that as the clothes leave one board and pass onto the adjoining one a relaxation of the pressure takes place upon the clothes, thus allowing the clothes to take in a supply of "suds" for a renewed pressure which had been expelled by their previous passage over one of the boards H'.

It is obvious that for "light" or "heavy" clothes the operator will govern the amount of pressure by applying more or less weight to the arm k.

Thus constructed my machine possesses all the requisite capabilities for washing delicate or heavy articles, is simple in its mechanism, not liable to get out of order, and effective in action.

Having thus described my invention, what I claim as new, and desire to secure by Letters Patent of the United States, is—

1. A rubbing-cylinder, B, armed with eccentric rubbers C, in the manner and for the purpose set forth.
2. A rubbing-board, H, having its rubbing-plates H' formed with a series of ribs h', h², h³, and h⁴, of increasing height, in the manner and for the purpose specified.
3. A rubbing-cylinder, B, in combination with a rubbing-board, H, substantially in the manner and for the purpose set forth.

N. B. CLABAUGH.
